Filed October 10, 1944. Serial No. 545,704. This application is a continuation-in-part of my application, Serial No. 545,704, filed October 10, 1944, for "Voice Operated Antisinging Repeater," now pending.

UNITED STATES PATENT OFFICE

VOICE OPERATED ANTISINGING REPEATER

Francis J. Blitz, Eatontown, N. J.

Application July 19, 1944, Serial No. 545,704

2 Claims. (Cl. 179—170)

Patent granted January 1, 1949. (Granted under the act of March 3, 1883, as amended April 30, 1928; 370 O. G. 757)

1 The invention described herein may be manufactured and used by or for the Government for governmental purposes, without the payment to me of any royalty thereon.

This invention relates to signal-controlled repeaters for two-way communication over a single line or channel.

In prior repeaters of this type, a limitation exists in the maximum permissible amplifier gain in order that self-oscillation, or "singing," be avoided. In one widely used system known as the type "22" repeater (two-element, two-way), a balanced-bridge circuit is used to prevent "singing." The gain of such repeater must, however, be kept low to avoid self-oscillation due to slight line unbalance. In systems using hybrid transformers, the unbalance must be so small that no transit tones will follow the loudest spoken word.

An important limitation of the balanced type of repeater is that half the energy is lost in the balancing network of the bridge, which loss, for reasons above mentioned, cannot be compensated for by providing high gain in the repeater. Moreover, since it is difficult to balance the bridge for a wide band of frequencies, filters are usually used to eliminate all frequencies not required for intelligibility. Consequently, systems of this type cannot generally be used where high fidelity is required.

It is a principal object of this invention to provide a two-way repeater system which can have high gain and/or high fidelity without being susceptible to self-oscillation. A further object is to provide a two-way repeater system which does not require any balancing.

For a detailed description of the invention, together with other and further objects thereof, reference is had to the following description taken in connection with the accompanying drawings, in which:

Figure 1 is a block diagram of the invention; and

Figure 2 is a schematic circuit diagram of the invention.

For a general description of the invention, reference is made to the block diagram in Fig. 1, wherein there is shown interposed in a single transmission line a pair of amplifying channels A and B for handling signals coming through directions W and E, respectively. Both channels are identical in structure, and respectively comprise input amplifier stages A_1 and B_1 , output amplifier stages A_0 and B_0 , and control stages A_c and B_c . Because of their connection to a

common transmission line, it will be seen that the input stage of one channel must necessarily be coupled to the output stage of the other channel. Under ordinary circumstances, feedback will take place and give rise to self-oscillation.

To avoid this condition, input stages A_1 and B_1 are, in the absence of signals, made normally operative; and output stages A_0 and B_0 are normally biased to cutoff by potentials from control stages A_c and B_c respectively. Each of said control stages will, in response to a signal from the input stage of its channel, first bias the input stage of the other channel to cutoff, and then unblock the output stage in its own channel so as to provide amplification and transmission of signals from the input stage in said channel.

For example, assume that a signal arrives from direction W. Input stage A_1 will amplify said signal and impose it upon control stage A_c and upon the normally blocked output stage A_0 . Control stage A_c will, in response to said signal, first generate a potential which is impressed, through line 100, as a blocking bias upon input stage B_1 in channel B. A short interval later, control stage A_c will remove the blocking bias from amplifier A_0 so that signals from the W direction can be amplified and transmitted over the line. The blocking of the input stage B_1 will prevent transmission of signals from the E direction, and will also prevent signals in the output stage A_0 from being fed back to the input stage A_1 , so that self-oscillation, and hence, "singing" in the repeater system is avoided.

Since channels A and B are identical and symmetrically connected with respect to each other and the transmission line, channel B will function in response to signals from the E direction in the identical manner as above described in connection with channel A.

For a more detailed description of the invention, reference is made to the circuit diagram in Fig. 2. The line is coupled to the repeater channels through three-winding transformers 10 and 10'. One coil 12 of transformer 10 is connected to the incoming line from direction W, and coil 12' of transformer 10' is connected to the line from the opposite direction E. Coils 14 and 14' of the transformers are connected to input stages A_1 and B_1 , respectively. Coils 16 and 16' are connected to output stages A_0 and B_0 respectively.

A signal arriving from direction W will be induced into coil 14 and a portion of the signal energy, as determined by adjustment of poten-

tiometer 18, will be impressed upon the grid of normally operative triode 20 of input stage A_i. The amplified output of said triode will be impressed across the primary of transformer 22, which has two secondaries 24 and 26. The output of secondary 24 is impressed, through blocking condenser 28, upon the grid of triode 30 of output amplifier A_o, but since said tube is normally biased to cutoff by the voltage drop across resistor 32 between its grid and cathode, the signals impressed thereon are not as yet transmitted. Resistor 32 is also in the plate circuit of the normally conducting triode section of diode-triode tube 34 in control stage A_c, so that the steady plate current through said resistor causes the voltage drop which is applied as a cutoff bias to the grid of tube 30. Voltage-dividing resistors 36 and 38, bypassed by the suitable capacitors, are connected in series across a B-voltage source (not shown) for supplying suitable plate potentials to tubes 30 and 34.

The signal voltage across secondary 26 is also rectified in a circuit including diode-anode 40 of tube 34, the cathode of said tube, to ground; and from ground through resistor 42, shunted by a capacitor 44, in the grid circuit of tube 20' of input amplifier B_i, and then back to secondary 26 through lead 100.

Another circuit from ground back to the secondary extends through resistor 46, shunted by capacitor 48, and through resistor 50. The voltage drop across resistor 42' biases tube 20' to cutoff, so that signals which might arrive from direction E, will not be transmitted.

A short interval later, due to the additional delay provided the series resistor 50, a voltage is developed across resistor 46 which renders grid 52 sufficiently negative to drive the triode section of tube 34 to cutoff. The resulting drop in plate current through resistor 32 will remove the cutoff bias from the grid of tube 30, whereby said tube is rendered operative to amplify signals from secondary 24 and transmit them over the line through transformer 10'. Since tube 20' of channel B is not conducting, no feedback to the input amplifier 20 of channel A can occur, so that "singing" is prevented.

The time constants of R-C components 42', 44', 46, 48, 50 is made sufficiently large to prevent decay of the voltages developed thereacross during the intervals between consecutive speech sounds, so that the circuits will not return to the normal, no-signal condition during said intervals. Said time constants are also such that, after signal transmission ceases, output stage A_o will be cut off slightly before input stage B_i becomes operative.

Channel B is, in every respect, identical with channel A, and functions for signals from the E direction in the same manner as channel A functions for signals in the W direction. The components of both channels are symmetrically connected with respect to each other and to the line. Components of channel B which are identical in structure and function as the corresponding components in channel A, are identified by the same reference numerals, but with a prime mark added. Thus signals arriving from direction E, will first cause a bias voltage to be developed across resistor 42 to block input amplifier A_i, and then de-

velop a voltage across resistor 46' which then causes output amplifier B_o to become inoperative.

Many changes may be made in the circuits above described. Instead of using potentiometers 18 and 18' to adjust the average levels of the incoming signals, conventional AVC circuits may be used for this purpose. The repeater may be adapted for use with a single transmission channel in one direction and a pair of transmission channels in the opposite direction, by using separate input and output transformers for said pair of channels. It will be obvious to those skilled in the art that various other changes and modifications may be made without departing from the true spirit and scope of the invention as defined in the appended claims.

I claim:

1. A two-way signal repeater system comprising a pair of amplifying channels; each channel having first and second amplifier stages, said first stage being normally operative and said second stage being normally inoperative; means to couple the first stage of each channel and the second stage of the other channel to a common section of a two-way transmission line; and means in each channel responsive to a signal in the output of the first stage in said channel to provide a bias voltage to render inoperative the first stage of the other channel, and a time delay circuit responsive to said bias voltage to provide a delayed bias voltage to render the second stage of said channel operative to amplify and transmit said signals from one to the other section of said transmission line.
2. A two-way signal repeater system comprising a pair of amplifying channels; each channel having a normally operative first amplifier stage, a second electron-tube amplifier stage, and an electron-tube control stage coupled to the output of said first stage; means to couple the first stage of one channel and the second stage of the other channel to each other and to a common section of a two-way transmission line; means responsive to normal plate-current flow in the electron tube in the control stage of each channel to bias the electron tube in the second stage of said channel to cutoff; and means responsive to a signal in the output of the first stage in one channel for developing a bias voltage to cut off the first stage of the other channel, and a time delay circuit responsive to said bias voltage to provide a delayed bias voltage to cut off the electron tube of the control stage in said one channel to reduce said normal plate-current flow sufficiently to remove said cut-off bias from the electron tube in the second stage of said one channel, thereby rendering said second stage operative to amplify and transmit said signals from one to the other section of said transmission line.
